P. M. RAINY

TELEGRAPH SYSTEM

Filed April 27, 1920

Inventor:
Paul M. Rainey
by Joel C. Palmer, Atty.

UNITED STATES PATENT OFFICE.

PAUL M. RAINY, OF GLEN RIDGE, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

Application filed April 27, 1920. Serial No. 377,080.

To all whom it may concern:

Be it known that I, PAUL M. RAINY, a citizen of the United States, residing at Glen Ridge, in the county of Essex, State of New Jersey, have invented certain new and useful Improvements in Telegraph Systems, of which the following is a full, clear, concise, and exact description.

This invention relates to telegraph systems and particularly to current impulse repeaters for use in such systems.

An object of the invention is the provision of an efficient, reliable and inexpensive repeating means whereby signaling impulses may be repeated from one line section to another free from bias and distortion.

This is accomplished by providing suitable receiving and distributing apparatus in combination with means for storing the signals as they are received from one line section, with additional distributing means for distributing the stored impulses to another line section.

This invention may be considered an improvement over the system disclosed and claimed in U. S. Patent #1,245,507, issued to me on November 6, 1917.

More specifically the preferred embodiment of the invention contemplates the employment of a vibrating reed or member having a natural period of motion in combination with a line relay for receiving and distributing the line impulses from one line section to a plurality of signal-storing relays. Cooperating with the storing relays is another vibrating reed or member having a natural period of motion, which may be called a transmitting distributor, for repeating the stored impulses to another line section.

This transmitting distributor reed vibrates with a definite time relation with respect to the former and preferably at one-half the speed of the receiving distributor reed.

The above and other objects of this invention will be fully set forth in the following description and claims, and will be more readily understood by reference to the accompanying drawing wherein the preferred embodiment is shown diagrammatically.

In the drawing, 1 and 2 represent two line

sections terminating at a repeating station A. Suitable transmitting and receiving apparatus may be associated with the line sections 1 and 2 at distant stations and may be of any desired type.

The current impulse-receiving distributor represented at the repeating station comprises a vibrating reed 5 mounted on a stationary support 6. The distributor reed 5 is controlled by a magnet 7, which is preferably a neutral magnet included in a circuit controlled by armature 4 of line relay 3. The distributor reed 5 has a definite fundamental frequency of vibration which, in the preferred form of the invention, is equal to twice the frequency at which the signals are received. The transmitting distributor reed 25 is mounted on a stationary support 26 and is controlled by a magnet 27 which is included in a circuit controlled by both of the distributor reeds. The receiving distributor 5 and transmitting distributor 25 cooperate to control the energizing circuits through the storing relays 20 and 21. The storing relays are arranged to be locked momentarily in their energized condition in order to provide a complete overlap in storing the signaling impulses and avoid any delay in the retransmission of the signals from one line section to another.

As previously stated, the receiving distributor reed 5 vibrates preferably at double the frequency of the transmitting distributor reed 25 and, therefore, an energizing circuit will be completed through one of the signal-storing relays whenever the reed 5 is in its uppermost position and whenever the reed 25 is in either its uppermost or lowermost position.

Let it be assumed that the receiving and transmitting reeds have been set in motion. In this connection it may be stated that the reeds may be set in vibration manually and thereafter controlled by line impulses or the vibration of the reeds may be initiated directly by the controlling magnets 7 and 27. It is customary in telegraph practice to send reversals of current over the line to start the repeating apparatus in operation and to balance the lines before message impulses are transmitted. Assuming that reed 5 is

in its uppermost position, so that contacts 3 are closed, and that reed 25 is in its uppermost position also so that contacts 30, 31 and 32 are closed. With the reed 5 in its 6 normal position as shown in the drawing, an energizing circuit for relay 27 is established over a circuit extending from battery, through contact 32, winding of relay 27, and the middle contact of reed 5 to ground. Relay 27 will thus be energized for attracting the reed 25 and upon the closure of the lower contact of reed 5, a similar circuit is completed so that for each movement of the reed 5, the associated reed 25 will be corrected. Then let it be assumed that at that instant an impulse is received over the line section 1 and through the windings of line relay 3, to cause the armature 4 to make engagement with its upper contact, thereby establishing a circuit from positive battery 9, relay armature 4, conductor 10, to the dividing point 11, where part of the current flows over one branch through the winding of magnet 7, to condenser 12, thereby causing the reed 5 to be momentarily attracted by magnet 7. Current also flows from the point 11 over the other branch through resistance 13, contacts 8 of distributor 5, thence to contacts 30 of distributor 25, and through the winding of relay 21 to negative battery 29. Relay 21 thereupon attracts its armatures 22 and 23. The attraction of left-hand armature 23 establishes a holding circuit momentarily for relay 21 which may be traced from positive battery 28, contacts 33 of distributor 25 (these contacts now being closed), conductor 34, armature 23 and front contact thereof, through the winding of relay 21 to negative battery 29. The spring contacts controlling the energizing and holding circuits of relay 21 are so adjusted that the contacts controlling the holding circuit for the relay are closed before the contacts controlling the energizing circuit are opened.

Now assuming that a second line impulse is received at the instant the distributor reed 5 has completed its first cycle of operation and is again in its uppermost position, bearing in mind that at this instant the distributor 25 is in its lowermost position, and further assuming that the second line impulse is of negative polarity thereby causing the relay armature 4 to engage the contact connected to negative battery 14, whereupon a circuit will be completed from grounded battery 14, armature 4 of line relay 3, conductor 10, to the dividing point 11. Now since condenser 12 was charged by the previous positive line impulse, this condenser will now discharge to negative battery 14 through the winding of magnet 7 and will cause it to attract the distributor reed 5, just as in the previous instance. A circuit will be established also from grounded battery 14 to the dividing point 11 as hereinbefore traced, resistance 13, contacts 8 of distributor 5, contacts 35 of distributor 25, and winding of relay 20 to negative battery 29. On account of the opposing batteries in this circuit relay 20 will not be caused to attract its armatures 36 and 37, but armature 36 will remain in engagement with its back contact, thereby connecting negative battery to the upper contact 38 of distributor 25. If the second line impulse had been a positive impulse, so relay 20 would have been energized in like manner to relay 21, would have established a holding circuit for itself through its left-hand armature, and would have connected positive battery through armature 36 to distributor contact 38. Now it will be observed that when the circuit just traced is completed through relay 20, the distributor reed 25 will be in its lowermost position and, when in that position, will complete a circuit from positive battery through armature 22 of relay 21, contact 24, distributor reed 25, conductor 40, to the apex of the polar relay 43 and out over the line section 2. Thus, while the second impulse is being received from line section 1, the first impulse is being transmitted in rejuvenated form to line section 2. Likewise when a third impulse is received and distributor reed 25 is in its uppermost position, a circuit will again be completed through storing relay 21 and the second impulse will be transmitted from battery and armature 36 of relay 20, contact 38, distributor reed 25, conductor 40, and through the winding of line 43, to line section 2, as previously traced. Thus it will be seen that as each impulse, after the first impulse, is being received and stored in one of the relays 20 or 21, the previously received impulse which was stored in the other of the two storing relays will be transmitted in rejuvenated form through the transmitter distributor contacts to the line section 2. This arrangement provides a complete overlap in the retransmission of the line signals and necessitates no delay in retransmission, thereby making it possible to transmit signals at the maximum line frequency.

It will be understood that various and numerous changes may be made in the system disclosed without departing from the spirit of the invention. For example, the storing relays 20 and 21 are illustrated as neutral relays provided with energizing and holding circuits. These relays may of course, be replaced by polar relays and in fact such use is contemplated.

What is claimed is:

1. A repeating system comprising a receiving distributor, a pair of relays asso-

- ciated therewith and invariably operated alternately by line current impulses, a transmitting current distributor, and a source of current adapted to cooperate with said transmitting distributor and controlled by said relays for transmitting impulses to an adjoining line circuit.
2. A repeating system comprising a receiving current distributor, a pair of signal storing relays associated therewith and operated alternately by line current impulses, a transmitting current distributor associated therewith, a holding circuit for each of said relays controlled by said distributor, and a source of current controlled by said relays and arranged to be connected to the line circuit through the transmitting current distributor.
3. A repeater comprising a member having a natural period of motion, a source of signaling current, and a pair of storing relays arranged to cooperate with said member for transmitting impulses to a line circuit.
4. A repeater comprising a member having a natural period of motion, electromagnetic means associated therewith and controlled by current impulses for controlling the movement of said member, and means selectively operated for storing the effects of current impulses which may be later applied to a connected line circuit through the instrumentality of said member.
5. A repeater comprising a member having a natural period of motion, electromagnetic means associated therewith and controlled by current impulses for controlling the movement of said member, and a pair of relays selectively operated for storing the effects of current impulses which may be later applied to a connected line circuit through the instrumentality of said member.
6. In combination with a telegraph system, a signaling conductor divided into sections, repeating means intermediate such sections comprising a plurality of signal storing devices, and a member having a natural period of motion for repeating signals stored in said devices to an adjoining line section.
7. In combination with a telegraph system, a signaling conductor divided into sections, repeating means intermediate such sections comprising a member having a natural period of motion associated with one of said sections, signal storing means responsive to the action of said member, and means for repeating the signals stored in said signal storing means to the adjoining line section.
8. In combination with a telegraph system, a signaling conductor divided into sections, repeating means intermediate such sections comprising a member having a natural period of motion associated with one of said sections, signal storing means responsive to the action of said member, and additional means having a natural period of motion for repeating current impulses as stored in said signal storing means to the adjoining line section.
9. A telegraph system comprising a line divided into sections, repeating apparatus interposed between adjacent sections thereof comprising receiving and transmitting current impulse distributors, said receiving distributor comprising a freely vibrating reed controlled by line current impulses, said transmitting distributor being controlled by said receiving distributor, a source of current and means for connecting said source of current to a line section through the instrumentality of said transmitting distributor.
10. A telegraph system for retransmitting signaling impulses from one line circuit to another, receiving and distributing means for receiving and distributing impulses received from one line section, transmitting current distributor means comprising a freely vibrating reed and controlled by said receiving distributing means, a source of current and means for connecting said source of current to a line circuit through the instrumentality of said transmitting distributor.
11. A retransmitting apparatus comprising a receiving current distributor, consisting of a member having a natural period of motion, electromagnetic means associated therewith and controlled by current impulses for controlling the speed of said distributor, a plurality of relays selectively operated by current impulses and controlled by said receiving distributor, a transmitting current distributor also comprising a member having a natural period of motion, and a source of current controlled by said relays and connected to a line circuit by said transmitting distributor.
12. A retransmitting apparatus comprising a receiving current distributor consisting of a member having a natural period of motion, electromagnetic means associated therewith and controlled by current impulses for controlling the speed of said distributor, a plurality of relays selectively operated by current impulses and controlled by said receiving distributor, a transmitting current distributor also comprising a member having a natural period of motion, electromagnetic means associated therewith and controlled by said receiving distributor for maintaining the speed of said distributors in definite time relation with respect to one another, and a source of current controlled by said relays and connected to a line circuit by said transmitting distributor.
13. A retransmitting apparatus comprising a receiving current distributor consisting solely of a freely vibrating reed, electro-

4 magnetic means associated therewith and reed and a source of current controlled by controlled by current impulses for controlling the speed of said distributor, a plurality of relays selectively operated by current impulses and controlled by said receiving distributor, a plurality of relays and connected to a line circuit by said transmitting distributor. In witness whereof, I hereunto subscribe my name this 24th day of April A. D., 1920.

10

PAUL M. RAINES.
